UNITED STATES PATENT OFFICE.

AUSTIN B. HAYDEN, OF CHICAGO, ILLINOIS, ASSIGNOR TO COMPUTING SCALE COMPANY OF AMERICA, A CORPORATION OF NEW JERSEY.

COMPUTING-SCALE.

SPECIFICATION forming part of Letters Patent No. 700,920, dated May 27, 1902.

Application filed April 6, 1901. Serial No. 54,667. (No model.)

To all whom it may concern:

Be it known that I, AUSTIN B. HAYDEN, a citizen of the United States, residing at Chicago, in the county of Cook and State of Illinois, have invented a new and useful Computing-
5 Scale, of which the following is a specification.

My invention relates particularly to computing-scales of the spring-balance type, my primary object being to provide a scale of
10 this class of large computing capacity and of simple construction.

My invention is illustrated in its preferred form in the accompanying drawings, in which—

15 Figure 1 is a view in front elevation of a spring-balance computing-scale embodying my improvements; Fig. 2, a central vertical section of the same, the load-pan being detached; Fig. 3, a transverse section taken as indicated at line 3 of Fig. 2, and Fig. 4 a fragmentary view showing a ball-cup connected with the lower end of the casing or frame.

25 A represents a vertically-disposed casing or frame portion which may be supported from any suitable frame or standard by means of the eye or loop *a* at its top; B, a vertically-disposed computing-cylinder contained within said casing; C, a vertically-disposed cylinder-actuating rod journaled in the casing A and having rigid connection with the cylinder B; D, a standard or spring-support located within the computing-cylinder and supported from the base or lower end of the casing A; 30 E, a spring-supported cylinder-actuating cross-head which serves also as a member of the load-supporting device; F, a clevis or stirrup supported from the member E, and G a load-pan supported from the clevis F.

35 The casing A comprises, preferably, an upper head or end *a*³, cylindrical body *a*², a lower end *a*³, and sight-glasses *a*⁴, *a*⁵, and *a*⁶, arranged in vertical slots with which the casing-front is provided. The head *a*³ is provided centrally with an adjustable ball-cup *a*⁷, having a stem *a*⁸, which has threaded connection with said lower end and is provided with a lock-nut *a*⁹. The casing ends are connected by rods *a*¹⁰, as shown. The rod C has a conical lower end which rests upon balls in the cup *a*⁷ and at its upper end is provided with

45 a conical recess, which receives the conical end of a screw *a*¹¹, connected with the upper end *a*¹ of the casing. It will thus be seen that the rod C and the computing-cylinder fixed thereto are adjustable vertically.

55 The computing-cylinder comprises a body or cylindrical portion *b* and an upper end *b*¹, through which the upper end of the rod C extends. There is of course sufficient space 60 between the cylinder B and the casing A to permit the cylinder to turn freely with the rod C. Said cylinder rotates in the direction indicated by the arrow in Figs. 1 and 2 when the load-pan is depressed. It is provided 65 with circumferential rows of cost-computations or value-indicating figures, a few only of which are shown. The casing A is provided with vertically-arranged columns of price-indicating figures located adjacent to 70 the margins of the sight-glasses *a*⁴ *a*⁶. The rows of value-indicating figures of the computing-cylinder should come opposite the appropriate price-indicating figures, and this is provided for in the vertical adjustment of 75 the rod C. The cylinder B is provided with circumferential rows of weight-indicating characters, located so as to pass beneath the sight-glass *a*⁵ when said cylinder is rotated. The casing A is provided with a fine vertically-disposed wire *c*, which crosses the sight-glasses mentioned and affords a reference-line or reading-line. The scale is shown at rest in Fig. 1, and in this position the zero-marks of the computing-cylinder are beneath 85 the wire *c*. Directly to the left of the wire *c* are shown certain of the cost computations which correspond to the highest weight which the scale can give—in this instance twenty-four pounds. The manner of supplying the 90 computing-cylinder with cost computations is now well understood in the art, and it is deemed unnecessary to give any detailed description thereof. In Fig. 1 I have shown the value-indicating figures from "5" to "15," 95 inclusive, arranged opposite the sight-glass *a*⁴ and the figures "16" to "30," inclusive, arranged opposite the sight-glass *a*⁶, the sight-glass *a*⁵ at which the weight-indicating figures are used being intermediate the glasses 100 *a*⁴ and *a*⁶.

The spring standard or support D comprises

vertical rods d , having threaded connection with the lower end of the casing A and provided with lock-nuts d' and a cross-bar d^2 at the upper ends of said rods and to which the 5 springs E' are attached. The cross-bar d^2 is provided with a central perforation through which the rod C loosely extends, and the lower end of the casing A is provided with perforations through which the vertical members of 10 the clevis F loosely extend.

The member E is provided at one end with a yieldingly-held roller f, which engages the adjacent standard-rod d, and centrally with a relatively large opening f', through which 15 the rod C extends. At the opening f' is journaled on screw-points f² a roller f³, which engages a spiral f⁴, with which the rod C is provided. In said opening f' is also located a yieldingly-held roller f⁵, which is close to or 20 in light contact with the adjacent cylindrical surface of rod C. The tension of the roller f⁵ may be regulated by a screw f⁶, as shown.

The operation of the scale will be readily understood from the foregoing description.

25 In assembling the parts the rod C may be vertically adjusted, and through the medium thereof the cylinder B is raised or lowered to bring its value-indicating rows into correct alignment with the price-indicating figures 30 of the casing. The standard D may be adjusted vertically to cause the cylinder through the medium of the rod C to rotate in one direction or the other to bring the zero-marks of the cylinder beneath the wire c. After 35 the adjustment has been properly made the article to be weighed is thrown upon the load-pan G, thereby depressing the clevis F and the cylinder-actuating member E. The member E is guided in its vertical movement by the 40 roller f, and hence is non-rotatable. Downward movement of the member E, therefore, causes the rod C to rotate in the direction indicated by the arrow in Fig. 2, thereby causing the computing-cylinder to rotate in the 45 direction indicated by the arrow in Fig. 1. The weight of the article will after this action appear beneath the wire c at the sight-glass a³, while the value will appear opposite the appropriate number of the price-index 50 and beneath said wire.

It will be understood readily that a scale of this description will come quickly to rest in the weighing operation, as the inertia of the computing-cylinder will always be in a 55 direction to oppose the reactive forces upon the member E, due to the springs E' and to the weight of the load.

Changes in details of construction within the spirit of my invention may be made. 60 Hence no limitation is to be understood from the foregoing detailed description except as shall appear from the appended claims.

What I claim as new, and desire to secure by Letters Patent, is—

65 1. In a spring-balance computing-scale, a vertically-disposed computing-cylinder, in combination with a cylinder-actuating rod

provided with a spiral, a rod-actuating vertically-movable non-rotatable cross-head engaging said spiral, and a load-support beneath 70 and suspended from said cross-head, substantially as described.

2. In a spring-balance computing-scale, the combination of a suitably-supported non-rotatable casing or frame provided with a price- 75 index, a vertically-disposed rotatable computing-cylinder in said casing, the same being provided with cost computations, a cylinder-actuating rod journaled in said casing and provided with a spiral, a spring-support, a 80 spring connected therewith, a load-support connected with said spring and a vertically-movable non-rotatable cross-head disposed vertically above and moving with said load-support and serving to actuate said rod, sub- 85 substantially as described.

3. In a spring-balance computing-scale, the combination of a suitably-supported vertical non-rotatable casing provided with a price- 90 index, a vertical rotatable computing-cylinder 95 in said casing provided with cost computations, a vertically-disposed cylinder-actuating rod supporting said cylinder and journaled in said casing, said rod being provided with a spiral, a spring-supporting standard within said cylinder and supported from the bottom of said casing, a spring supported thereby, a vertically-movable cross-head supported from said spring and having engagement with the spiral of said rod for imparting 100 rotary movement to said rod, and a spring-supported load-pan, substantially as described.

4. The combination of a suitable frame or casing provided with a price-index, a vertically-disposed computing-cylinder provided with cost computations, a spiral-equipped cylinder-actuating rod supporting said cylinder and having adjustable bearings at the ends of said casing, a spring-supporting standard 110 within said cylinder and supported from said casing, a spring supported thereon, a vertically-movable cross-head engaging the spiral of said rod and serving to rotate the rod, and a spring-supported load-receiving pan or plat- 115 form, substantially as described.

5. In a spring-balance computing-scale, a suitable casing, a computing-cylinder, a spring-supporting standard of adjustable height supported within said casing, a spiral-equipped cylinder-actuating rod supporting said cylinder and journaled in said casing, a spring connected with said standard, a vertically-movable cross-head engaging the spiral of said rod and serving to actuate said rod, 125 and a spring-supported load-receiver vertically beneath and actuating said cross-head, as described.

6. In a spring-balance computing-scale, the combination of a suitably-journaled vertically-disposed spiral-equipped cylinder-actuating rod, a computing-cylinder fixed to rotate therewith, a spring-support, a vertically-movable cross-head within said cylinder and

having engagement with the spiral of said rod and serving to rotate said rod, and a spring-supported load-receiver moving with said cross-head, substantially as described.

5 7. In a computing-scale, the combination of a suitably-journalized vertically-disposed spiral-equipped cylinder-actuating rod, a computing-cylinder fixed to rotate therewith, a spring-support, a spring, a vertically-movable cross-head, antifriction-bearing between said cross-head and spiral of said rod, and a spring-supported load-receiver vertically beneath and actuating said cross-head, substantially as described.

15 8. In a spring-balance computing-scale, the combination of a suitably-journalized vertically-disposed spiral-equipped cylinder-actuating rod, a computing-cylinder fixed to rotate therewith, a spring-support, a spring, a

vertically-movable cross-head provided with 20 spiral-engaging means, a spring-supported load-receiver, and a vertical guide for said cross-head, substantially as described.

9. In a scale, the combination of a casing, a spring-supporting standard supported from 25 the lower end of said casing, a computing-cylinder inclosing said standard, a spiral-equipped rod fixed to rotate with said cylinder, a spring, a vertically-movable cross-head engaging the spiral of said rod, a guide for 30 said cross-head, antifriction-bearing between said cross-head and guide and a spring-supported load-receiver, substantially as described.

AUSTIN B. HAYDEN.
